CAR TOP LUGGAGE CARRIER

Edward J. Schoening, 9726 S. Charles St.,
Chicago, Ill. 60621

Filed Jan. 20, 1975, Ser. No. 542,171

Term of patent 14 years

Int. Cl. D12—16

U.S. Cl. D12—157

Fig. 1

Fig. 2

Fig. 3

Fig. 4

Fig. 5

Fig. 6

Fig. 7

FIG. 1 is a perspective view of a car top luggage carrier embodying the present design and illustrating the carrier in closed position;

FIG. 2 is a perspective view thereof illustrating the carrier in opened position;

FIG. 3 is a front elevational view of FIG. 1;

FIG. 4 is a rear elevational view of FIG. 1;

FIG. 5 is a top plan view of the base of the carrier with the cover removed and the support brackets omitted for convenience of illustration.

FIG. 6 is a top plan view of FIG. 1; and

FIG. 7 is an elevational view of the side opposite that shown in FIG. 1.

The bottom of the carrier is substantially plain and unornamented.

I claim:

The ornamental design for a car top luggage carrier, substantially as shown and described.
